FLATWARE DISPLAY RACK

Elmer L. Reibold, Park Ridge, Leon E. Litzelman, Naperville, and Robert W. Masco, Chicago, Ill., assignors to Oneida Ltd., Oneida, N.Y., a corporation of New York

Filed May 1, 1963, Ser. No. 74,695

Term of patent 14 years

(Cl. D80—10)

FIG. 1

FIG. 2

FIG. 3

Des. 198,890

PAGE 2

FIG. 6

FIG. 1 is a perspective view of a flatware display rack embodying our new design;

FIGS. 2 and 3 are, respectively, enlarged elevational views taken from opposite sides thereof;

FIG. 4 is an enlarged elevational view taken from the front thereof, the broken line representations of flatware being for purposes of illustration only;

FIG. 5 is an enlarged plan view taken from the top thereof; and

FIG. 6 is an enlarged plan view taken from the bottom thereof.

We claim:

The ornamental design for a flatware display rack, substantially as shown and described.
